DESIGN FOR A REFRIGERATOR

Egmont Arens, New York, N. Y.

Application February 3, 1943, Serial No. 109,413

Term of patent 7 years

To all whom it may concern:

Be it known that I, Egmont Arens, a citizen of the United States and a resident of the city of New York, Borough of Manhattan, in the county and State of New York, have invented a new, original, and ornamental Design for a Refrigerator, of which the following is a specification, reference being had to the accompanying drawing, forming part thereof.

Fig. 1 is a front perspective view of a refrigerator, showing my new design;

Fig. 2 is a side elevational view; and

Fig. 3 is a top plan view thereof.

I claim:

The ornamental design for a refrigerator, substantially as shown.

EGMONT ARENS.
